Patented Jan. 24, 1922.

UNITED STATES PATENT OFFICE.

JOSEPH BACHRACH, OF NEW YORK, N. Y.

INKWELL.

1,404,681.

Specification of Letters Patent. Patented Jan. 24, 1922.

Continuation of application Serial No. 340,918, filed November 26, 1919. This application filed November 4, 1920. Serial No. 421,633.

To all whom it may concern:

Be it known that I, JOSEPH BACHRACH, a citizen of the United States, and a resident of the borough of Manhattan, city, county, 5 and State of New York, have invented certain new and useful Improvements in Ink-wells, of which the following is a specification.

This invention relates to ink-wells and the 10 present application is a substitute for and a continuation of a prior application, filed by me on November 26, 1919, Serial No. 340,918.

It is the primary purpose and object of the present invention to provide an ink-well of the self-closing type which is of 15 such construction that dust and other extraneous foreign matter will be effectually excluded from the ink chamber.

It is also a more particular object of my invention to provide a self-closing ink-well of 20 the type generally preferred for office use having a removable top or cover extending over the ink receiving chamber, said cover being provided with a rectangular opening 25 therein, together with a pair of sensitively mounted counter-balanced closure members pivotedly movable in said opening and normally completely closing the same. These 30 closing members are so constructed and arranged that they are wholly contained within the cover opening and do not project into the ink receiving chamber, said members readily yielding to the pressure of the pen point so that the latter will not in any manner 35 be injured when the pen point is inserted into the ink chamber, or withdrawn therefrom.

It is an important object and purpose of my present construction to provide upon the 40 cover of the well and the closure members which are mounted therein co-acting means which will absolutely prevent any possibility of the closure members being displaced or disconnected from the cover when they are 45 moved from their normally closed positions by the users of pens, and which means will permit of the position or manual disassembly or separation of the closure members and the cover only when said members occupy a certain definite position within the 50 cover opening.

My invention has for a further object to provide a form and construction of the cover and the closure members which will 55 permit of easy and quick disassembly of the parts for cleansing purposes while at

the same time, when said closure members are in their normal closed positions within the cover opening, they will provide a substantially air and dust tight closure for said 60 opening and the ink chamber.

It is a further object of my invention to simplify the construction of devices of this character whereby their manufacturing cost may be reduced to a minimum, and at the 65 same time enhance the ornamental and attractive appearance of the ink-well as a whole.

With the above and other objects in view, 70 my invention comprehends the provision of an ink-well characterized in the particulars above referred to, and in the form, construction and relative arrangement of its several parts, as will be hereinafter more fully described, illustrated in the accompanying drawing, and subsequently incorporated in the subjoined claims.

In the drawing wherein I have illustrated one practical embodiment of the invention 80 and in which similar reference characters designate corresponding parts throughout the several views:

Figure 1 is a longitudinal sectional view of an ink-well constructed in accordance with one embodiment of my invention and 85 showing one of the closure members in full lines in its normal closed position and the other of said closure members in dotted lines in an open position;

Figure 2 is a top plan view of the well, 90 one of the closure members being removed;

Figure 3 is a transverse section taken on the line 3—3 of Figure 2; and

Figure 4 is a bottom plan view of one of the closure members.

Referring in detail to the drawing the body 5 of the ink-well is preferably formed in the usual manner of moulded glass, but if desired may be constructed of other materials and in many other sizes and ornamental shapes than that indicated in the drawing.

This body 5 is provided with the chamber or cavity 6 for the reception of the ink, and upon its upper surface said body is formed with the raised or upstanding longitudinal marginal flanges 7, said flanges at their ends being inwardly extended for a short distance transversely of the well body as at 7'. These flanges are laterally spaced from the 110 upper edges of the chamber 6 as clearly shown in Figures 1 and 3 of the drawing.

The removable top or cover 8 for the ink-well is constructed of a suitable composition material, and as herein shown is of rectangular form in plan. This cover is 5 adapted to be seated upon the upper surface of the well body 5 within the flanges 7, 7'. The dimensions of the cover are such that a certain amount of freedom is allowed between the outer face of the cover wall and 10 said flanges so as to obviate sticking of the cover to the glass surfaces, which might offer some difficulty in removing the cover.

The cover 8 is provided with a central longitudinally elongated rectangular opening 9 and at the upper surface of said cover, the edges of the opening at the opposite ends thereof are recessed or rabbeted as at 10 to provide the horizontal shoulders 11. At the center of the opening 9, the opposite side 20 walls thereof are bevelled or inclined downwardly and inwardly as at 12, each of said bevelled surfaces being formed in an inwardly projecting inverted triangular shape portion 13 of the cover, the lower end or 25 apex of which, indicated at 14, terminates at a point in spaced relation to the lower edge of the cover. The concave bevelled surfaces 12 thus provided at opposite sides of the opening 9 constitute means for directing the pen point for proper engagement with the closure members as will be more fully understood from the following description.

The projections 13 on the side walls of 35 the opening 11 are produced by cutting away or recessing said side walls as shown at 15 and 16. The recesses 15 extend horizontally below the apexes 14 of the projecting portions 13, while the recesses 16 constitute 40 obliquely extending channels which extend upwardly from the apexes 14 to the rabbeted edges 10 of the cover. At the upper ends of these channels the horizontally extending shoulders 11 are formed with the 45 pivot seats or recesses 17, upon which the closure members are mounted for pivotal or rocking movement. The lower sides of these seats extend obliquely upwardly to the shoulders 11, so that it will be understood 50 that the provisions of these seats results in a natural widening of the upper ends of the channels 16.

The closure members 19 are of identically 55 the same form and construction. Each of these members, which is preferably of the same material as the cover 8, includes a body portion 20, the upper side of which is provided with laterally projecting flanges 21. At one end this body is formed with an 60 obliquely disposed relatively thin lip or extension 22, said lip 22 being preferably connected to one end of the body 20 by a longitudinally extending web 23. At the juncture of this web with the flanges 21 the 65 pivot lugs 24 are formed on the under sides

of said flanges, said lugs having the convex faces 25. These faces of the pivot lugs and the concave faces of the seats 17 describe arcs having their centers located at the upper corners of the projections 13 on the walls of 70 the cover 8. The upper open ends of the recesses or seats 17 are closed by means of the flanges 21 and the pivot lugs 24.

At its free lower end the lip 22 is rounded or convex as at 26, and is provided at opposite sides with the transversely projecting rounded lugs or extensions 27.

In assembling the closure members within the cover, the lugs 27 are engaged in the upper open ends of the inclined channels 15, 80 and said closure members moved downwardly in the opening 9 until the laterally projecting flanges 21 seat upon the shoulders 11. In this normal position of the two closure members, the convex surfaces 26 at the lower 85 ends of the lip 22 are in contact at the apexes 14 of the projections 13, and the lip extensions 27, and the side edges of the lips 22 extend beneath these overhanging or projecting parts of the cover as clearly shown 90 in Figures 2 and 3 of the drawing while the convex surfaces 25 of the lugs 24 are engaged upon the seats 17. It will be observed that in this position the lugs or extensions 27 are disposed immediately below the salient portions 28 formed on the opposite side walls of the opening 9 at the juncture of the recesses 15 and channels 16.

When the pen is inserted into the ink chamber, the pen point, regardless of the direction from which it is projected into the opening 9 of the cover, will be directed either by the inclined surfaces of the lips 22 or the conical inclined surfaces 12 between the contacting convex surfaces 26 of the closure members. The pressure of the pen point upon these convex faces causes the closure members to separate or open, the lugs 24 rocking freely on the seats 17, so that the closure members will move to positions approximating that illustrated in dotted lines in Figure 1 thereof. Of course, there may be a greater movement of one of these members than of the other, depending upon which member is subjected to the greatest pressure. In this movement of the closure members to open position the lugs 27 will move beneath the salient projections 28 and into the recesses 15 on the side walls of the opening 9. In this manner the pen may be 100 freely inserted, without obstruction or retardation by the closure members, into the ink chamber. It will be observed that the relatively heavy body portion 20 is disposed wholly on the opposite side of the pivot center of the closure member from the lip 22, so that as the pen is withdrawn this body, which serves as a counter-balancing medium, will immediately return the closure member 110 to its normal position. Thus the convex 115

faces 26 will at all times bear against the opposite sides of pen, and as the pen point is drawn upwardly between these faces the surplus ink is drained therefrom back into the ink chamber. As is well known, certain types of pen points have their edges irregularly formed and provided with recesses and projections. Certain types of pen-points are provided with projections on their edges which might possibly catch on the opposed ends of the closure members as the pen is withdrawn and lift the pivots from their seats, thus resulting in the complete detachment of the said members from the cover. My improved device prevents such possible displacement of the closure members. This is due to the fact that except when said closure members are disposed in a certain definite position in the cover opening, the lugs or extensions 27 thereof are out of alignment with the channels 16 and extend beneath the salient projections 28 on the side walls of the cover opening. Accordingly, it is seen that these lugs render it entirely impossible for the pivot lugs 24 of the closure members to lift from their seats 17 during the operation of the device. When it is desired to remove the closure members from the cover for the purpose of cleaning the same they are moved upwardly while disposed with their lugs 27 in line with the channels 16. In the illustrated embodiment of the invention I have shown the channels 16 located and arranged so that the lugs 27 are in alignment therewith when the closure members are in their normal closed positions. It will be understood, however, that this is not an essential consideration as these channels might be otherwise arranged.

From the foregoing description, considered in connection with the accompanying drawing, the construction, manner of operation and several advantages of my improved ink-well will be fully understood. It is to be observed that when the cover members are in their normal closed positions, the flanges 21 thereof, seat within the rabbeted edges of the opening 9, and the upper surfaces of said closure members are entirely flush with the upper surface of the cover. Thus, there are no parts of the closure members projecting exteriorly of the opening 11 and beyond the surface of the cover.

My invention is primarily designed for use in connection with low or flat rectangular ink-wells of the type generally preferred for office use, and by reason of the construction and mounting of the closure members in the cover, as above explained, it will be appreciated that the ornamental and attractive appearance of ink-wells of this type is maintained and enhanced. Nevertheless, the parts can be easily and quickly assembled or disassembled, and may be readily cleaned and the chamber replenished with ink when

necessary. Owing to the complete closure of the opening in the cover 8 by the members 19, dust or dirt is effectually excluded from the well cavity or chamber, so that the contents thereof will be kept in a free flowing condition, and excessive evaporation of the ink prevented.

I have herein shown and described an embodiment of the invention which I have found satisfactorily meets every requirement of an ink-well of this type, and which is handy, convenient and serviceable in practical use. It is, however, to be understood that the device may also be applied to ink-wells of various other forms, and that the several cooperating elements above referred to and the detail features thereof are also susceptible to many modifications. I, accordingly, reserve the privilege of adopting all such legitimate changes as may be fairly embodied within the spirit and scope of the invention as claimed.

I claim:

1. An ink-well comprising a body having an ink chamber, a cover for said chamber provided with an opening, a counter-balanced closure member removably associated with said cover, one of said parts having pivot lugs and the other being provided with recesses to receive said lugs, and one of said parts being further provided with means to close the open ends of said recesses.

2. An ink-well comprising a body having an open top ink chamber, a removable cover for said chamber having an opening therein, a pair of counter-balanced closure members normally closing said opening and each having integral pivot lugs, said cover being provided with recesses at opposite sides of the opening therein to receive said pivot lugs and flanges on said closure members overlying said recesses.

3. An ink-well comprising a body having an ink chamber, a removable cover for said chamber provided with a rectangular opening therein, counter-balanced closure members for said opening removably associated with said cover, the closure members and the cover having coacting means pivotally supporting the closure members in operative position, and said cover having stop shoulders limiting the movement of the closure members to their normal closing positions.

4. An ink-well comprising a body having an open top ink chamber, a removable cover for said chamber having a rectangular opening therein and pivot receiving recesses in the opposite side walls of said opening and in spaced relation to each end thereof, a pair of closure members closing said opening, each having pivot lugs intermediate of its ends for removable engagement in the corresponding recesses, and said members having opposed inwardly and downwardly inclined

- portions normally contacting with each other at their extremities, said cover having shoulders at the opposite ends of the opening and the closure members adapted for engagement upon the respective shoulders to limit the pivotal movement of said members to their closed positions and means carried by said members to close the open sides of said pivot receiving recesses.
- 10 5. An ink-well comprising a body having an ink chamber, a cover for said chamber provided with an opening, closure members for said opening, said closure members and the cover having separable coacting means 15 to pivotally support the closure members upon the cover and each of the closure members having flanges projecting laterally upon the edges of the opening in the cover.
6. An ink-well comprising a body having 20 an open top ink chamber, a removable cover for said chamber having an opening therein, a pair of counter-balanced closure members normally closing said opening and each having integral pivot lugs, said cover being 25 provided with recesses at opposite sides of the opening therein to receive said pivot lugs, and longitudinal flanges on said closure members overlying said recesses, said cover having stop shoulders upon which said 30 flanges are normally engaged.
7. An ink-well comprising a body having an ink chamber, a cover for said chamber having an opening therein, a closure member for said opening associated with said cover, 35 said closure member and the cover having coacting means permitting of the disconnection of said member from the cover only when the closure member is in its normal closed position and preventing such disconnection in all other positions of the closure member.
8. An ink-well comprising a body having 40 an ink chamber, a cover for said chamber having an opening therein, a closure member for said opening pivotally mounted upon the cover, said closure member and the cover having coacting means permitting of the disconnection of said member from the cover only when the closure member is in its normal closed position, and preventing such disconnection in all other positions of the closure member.
9. An ink-well comprising a body having 45 an ink chamber, a cover for said chamber having an opening therein and pivot receiving recesses in the opposite side walls of said opening, a closure member associated with the cover and having pivot lugs adapted to be engaged in the respective recesses, 50 said closure member and the cover being further provided with coacting means permitting of the disconnection of said member from the cover only when the closure member is in its normal closed position,

and preventing such disconnection in all other positions of the closure member.

10. An ink-well comprising a body having an ink chamber, a cover for said chamber having an opening therein, a pair of closure members arranged in opposed relation within said opening, said cover having open ended recesses and the closure members provided with pivot lugs for engagement in said recesses, said closure members and the cover also having additional means 75 permitting of the disconnection of said members from the cover only when the closure members are in their normal closed positions, and preventing such disconnection in all other positions of the closure members. 80

11. An ink-well comprising a body having an ink chamber, a removable cover for said chamber having an opening therein, a pair of counter-balanced closure members normally closing said opening, said cover having open ended recesses at opposite sides of the opening and the closure members provided with pivot lugs for engagement in said recesses, and means automatically rendered operative upon a movement of either of the 85 closure members from its normal closed position to prevent the disengagement of the pivot lugs thereon from the recesses in the cover.

12. An ink-well comprising a body having an ink chamber, a removable cover for said chamber having an opening therein and provided in the opposite side walls of said opening with open ended pivot receiving recesses and obliquely disposed channels 100 communicating with the respective recesses and converging towards each other downwardly therefrom, and a pair of counter-balanced closure members adapted to be arranged in opposed relation within said opening and each having pivot lugs for engagement in the corresponding recesses on the opposite side walls of the cover opening, each of said closure members being further provided with transversely projecting 105 lugs movable through said channels and permitting of the disconnection of said members from the cover when the closure members are in their normal closed positions, the side walls of the cover opening having additional means with which said lugs of the closure members coact to prevent such disconnection in all other positions of the closure members. 110

13. An ink-well comprising a body having 120 an ink chamber, a cover for said chamber provided with an opening, and counter-balanced closure members pivotally mounted upon the cover within said opening and having rectilinearly extending upper surfaces 125 flush with the upper surface of the cover when said members are in their normal closed positions.

14. An ink-well comprising a body having an ink chamber, a cover for said chamber provided with an opening, and counterbalanced closure members for said opening 5 pivotally mounted upon the cover having means coacting with the cover to prevent detachment of the closure members when the latter are moved from their normal closed positions, said closure members having rectilinearly extending upper surfaces occupying the same plane as the upper surface of said cover in the closed positions of 10 said members.
15. An ink-well cover having an opening
- therein, closure members for said opening 15 movably mounted upon said cover, said closure members and the cover having coacting means permitting of the disconnection of the closure members from the cover in one position of said closure members with respect to the cover but preventing such disconnection in all other positions of said closure members.

In testimony that I claim the foregoing as my invention, I have signed my name hereunder.

JOSEPH BACHRACH.
